UNITED STATES PATENT OFFICE

138,331

DESIGN FOR A SNOOD OR SIMILAR ARTICLE

Lilly Daché Després, New York, N. Y., assignor, by mesne assignments, to Weco Products Company, Chicago, Ill., a corporation of Illinois

Application November 13, 1943, Serial No. 111,680

Term of patent 14 years

(Cl. D86—10)

To all whom it may concern:

Be it known that I, Lilly Daché Després, a citizen of the United States and a resident of the city of New York, in the county of New York and State of New York, have invented a new, original, and ornamental Design for a Snood or Similar Article, of which the following is a specification, reference being had to the accompanying drawing, forming a part thereof.

On the drawing:
The figure illustrates a plan view of the snood or similar article, showing my new design.

I claim:
The ornamental design for a snood or similar article, as shown.

LILLY DACHÉ DESPRÉS.
